UNITED STATES PATENT OFFICE.

HENRY W. LENGFELDER, OF BELLEVILLE, ILLINOIS, ASSIGNOR TO
MITCHELL-PARKS MANUFACTURING CO., OF ST. LOUIS, MISSOURI, A CORPORATION OF MISSOURI.

METHOD OF PACKING FLASKS.

No. 840,070.

Specification of Letters Patent.

Patented Jan. 1, 1907.

Application filed June 28, 1906. Serial No. 323,947.

To all whom it may concern:

Be it known that I, HENRY W. LENGFELDER, a citizen of the United States, residing at Belleville, in the county of St. Clair and State of Illinois, have invented new and useful Improvements in Methods of Packing Flasks, of which the following is a specification.

This invention relates to the art of molding, and has reference to a novel method of packing the sand in the flask containing the pattern. This operation, so far as I am aware, has heretofore invariably been performed manually, requiring the services of quite a number of men for large moldings and the expenditure of considerable time in packing each flask.

According to my invention the sand is caused to pack in the flask automatically, as it were, by being discharged from a point a considerable distance above and in line with the flask, and this distance is great enough (say from fifteen to thirty feet) to permit the sand thus discharged to acquire under the law of falling bodies great momentum. The sand will thus strike the flask with much force and instantly conform to the configuration of the pattern. Not only so, but as succeeding quantities of sand fall into the flask the force of their fall will of course cause the sand to pack therein, and, in addition, their impact with the preceding body of sand already in the flask will cause such sand to be packed more securely in the flask and to be pressed uniformly in and about the pattern therein. In actual experience I am able by the use of my method to pack very large flasks in a fraction of a minute, and a single operator can do this work and pack many more flasks per hour than is possible under the old system with any number of workmen to a flask.

The above expresses in a general way the nature and advantages of my invention and, so far as the theory involved is concerned, is correct. In practice, however, I have found that the mere discharge of the sand from an elevated position is not sufficient to cause it to pack in the flask, for under such conditions the sand will fall in a shower—that is, in a stream composed of loose or disunited

lumps and individual grains—and these small unconnected bodies of sand will never acquire the momentum necessary to cause the sand to pack in the flask, and the succeeding individual quantities of sand will not have weight or momentum sufficient to materially increase the packing or compression of the sand already in the flask. To successfully make use of gravity in packing flasks, therefore, I have discovered and demonstrated that the sand must be discharged in separate compressed or at least compact bodies of considerable magnitude, and such bodies falling as units through space acquire a high degree of momentum and strike the flask with such force that in reality the sand is caused to pack much more firmly than when pressed in by hand in the ordinary way.

While the size of the wads or bodies of sand may vary, I have found it desirable to have each wad about as long as the flask is wide and substantially four or five inches in thickness. The wads are discharged to fall at right angles to the longitudinal axis of the flask, and the latter is moved back and forth on a truck or otherwise until it is filled.

I have illustrated in the accompanying drawings a suitable form of apparatus for carrying out my invention, such apparatus, however, not being my invention, but forming part of a system of molding invented by others and embodied in an application for patent filed of even date herewith.

In said drawings, Figure 1 is a view in side elevation and partly broken away of an apparatus by means of which my invention may be successfully practiced, and Fig. 2 is a view of that part of the apparatus above the floor-line and shown in front elevation.

Referring now to the drawings, the numeral 1 indicates the floor of the molding-room; 2, a track thereon; 3, a truck mounted to travel on said track, and 4 a flask inclosing a pattern and mounted on said truck ready to have the sand packed therein. Beneath an opening in the floor is mounted a sand-receptacle 5, containing a hopper 6, the lower end of which is closed by a feed-roller 7, located, as shown, some distance above the bottom of the receptacle 5. At the top of

the hopper 6 and immediately under the opening in the floor is suitably mounted a screen 8, which is agitated by means of a rod 9 and crank or eccentric 10, operated from any suitable source of power. Mounted in the lower part of the receptacle 5 are two sprocket-wheels 11, and mounted on rafters or other supports 12, located a suitable distance (say thirty feet) above the floor are two similar sprocket-wheels 13, and two sprocket-chains 14 pass over the respective sets of sprocket-wheels 11 13 and are connected to form an endless carrier by a series of L-shaped buckets 15, which are of a length to pass freely between the respective pairs of sprocket-wheels 11 and 12 and between two pairs of guide-pulleys 16 17, mounted in suitable bearings on the floor 1. The lower part of the receptacle 5 is provided with an inclined partition 18 to form a compartment 19 to receive the sand fed from the hopper by the feed-roller 7, and a curved depression 20 is provided in the floor of the compartment 19 to accommodate the troughs in passing around the sprocket-wheels 11. In passing through the compartment 19 each bucket 15 will take up a quantity of sand, as will be understood. Said buckets then pass in succession through a trough 21, the outer edge of said buckets at each end resting upon rails 22, provided on the bottom of the trough at opposite sides thereof, so that the outer edge of each bucket will be maintained a slight distance (say an eighth of an inch) above the bottom of the trough to allow the surplus sand carried out by the buckets or sand falling therefrom to slide back into the compartment 19.

23 indicates a packing-plate which is weighted at its outer end, as indicated at 24, and mounted on a rod 25, which is pivotally supported in bearings 26, mounted on the floor 1.

27 indicates a support for the packing-plate.

As each bucket passes out of the trough 21 and beyond the guide-pulleys 16 its bottom assumes a substantially horizontal position, and immediately thereafter it comes in contact with the under side of the packing-plate, which operates to press or pack the sand in the bucket. The packing-plate will be raised as the bucket travels upward, and as the latter passes from beneath it will fall back on the support 27 in position to be engaged by the next bucket. As each bucket passes around the sprocket-wheels 13 it will be turned gradually upside down, and when the bottom assumes a substantially horizontal position the wad of sand will be discharged therefrom and fall down into the flask on the truck, as represented in the drawings. The guide-pulleys 16 and 17 are for the purpose of giving the proper inclination to the lower

part of the endless elevator, so that the buckets will scoop up the sand as they pass through the compartment 19, and to the upper part, so that the wads will be discharged outside the line of travel of the buckets. The endless carrier or elevator is driven from a pulley 28, secured on the end of the shaft 29, on which the sprocket-wheels 13 are mounted.

It will be observed that the bodies or wads of sand are discharged successively or intermittently, and this characteristic of the method is one which contributes in a large measure to its successful employment, as the operator by moving the flask in an appropriate manner can insure such wads falling into the flask in positions best suited to insure the firm packing of the sand about the pattern and within the flask—that is to say, initially the flask is moved so that each wad will strike full upon the pattern or in spaced relation to each preceding wad throughout the length of the pattern. Succeeding wads may be similarly caused to fall between each two preceding wads, producing a wedging action and causing the sand to be packed solidly in the flask, this continuing until the flask is filled. The direct impact of one wad of sand upon another would have a tendency to cause the former to break and scatter, and thus not pack so firmly, and this tendency is practically prevented by causing the wads to fall into position in the flask in the manner described.

I claim—

1. In the art of molding, the method which consists in discharging into a flask a series of compact bodies of sand from a sufficient height above the flask to cause the sand to pack therein by impact therewith due to its fall.

2. In the art of molding, the method which consists in discharging into a flask a series of compressed bodies of sand from a sufficient height above the flask to cause the sand to pack therein by impact therewith due to its fall.

3. In the art of molding, the method which consists in compressing a series of bodies of sand and discharging the same at a sufficient height above the flask to cause the sand to pack therein by impact therewith due to its fall.

4. In the art of molding, the method which consists in successively discharging separate bodies of sand in compact form into a flask from a sufficient height above the flask to cause the sand to pack therein by impact therewith due to its fall.

5. In the art of molding, the method which consists in compressing the sand into separate wads, and intermittently discharging said wads at a sufficient height above a flask to cause the sand to pack therein by impact therewith and with preceding bodies of sand.

6. In the art of molding, the method which
consists in discharging into a flask a series of
compact bodies of sand, whose length is ap-
proximately equal to the width of the flask to
be packed, from a sufficient height above the
flask to cause the sand to pack therein by im-
pact therewith due to its fall.

In testimony whereof I have hereunto set
my hand in presence of two subscribing wit-
nesses.

HENRY W. LENGFELDER.
